UNITED STATES PATENT OFFICE.

FREDERICK BAKER, OF BRIGHTON, NEAR MELBOURNE, VICTORIA, AUSTRALIA.

MECHANISM FOR SUPPLYING THREAD TO BOBBINS IN LOOPERS.

1,029,335.

Specification of Letters Patent. Patented June 11, 1912.

Application filed May 25, 1904. Serial No. 209,625.

To all whom it may concern:

Be it known that I, FREDERICK BAKER, a subject of the King of Great Britain, residing at "Rockview" Beach Road, Brighton, near Melbourne, in the State of Victoria, Commonwealth of Australia, builder, have invented certain new and useful Improvements in Mechanism for Supplying Thread to Bobbins in Loopers, of which the following is a specification.

This invention relates to an attachment for sewing machines having revolving hooks and bobbins, the object of the invention being to provide efficient mechanism for winding the thread for such bobbin and for transferring it to the bobbin, without requiring the removal of the latter from the machine.

The invention is hereinafter more fully described and its essential characteristics are set out in the claims.

In these inventions the thread for the supply of the revolving hook is automatically wound into a spool upon a spindle or mandrel while the machine is working and can be slid onto a spindle contained in the revolving hook when it is desired to replenish the supply of thread for the revolving hook.

In order that my invention may be clearly understood I will describe it by reference to the accompanying drawings, in which:—

Figure 1 is an under side plan of a rotary shuttle sewing machine embodying my invention. Fig. 2 is a front elevation of the left hand portion of the lower part of said machine. Fig. 2^a is a front elevation of the right hand portion of the lower part of the machine,—this figure being a continuation of Fig. 2; Fig. 3 is a back elevation (partly in section) showing the mechanism winding a spool. Fig. 4 is a similar view to Fig. 3, but showing the mechanism pushing a wound spool into the revolving hook. Fig. 5 is an end elevation of my invention, being taken from the left hand end of the machine and omitting the supply reel. Fig. 6 is a vertical transverse section on line 6—6 of Figs. 1 and 3. Figs. 7 and 8 are views of a detail of the mechanism. Fig. 9 is a vertical longitudinal section on line 9—9 of Fig. 1. Figs. 10, 11, 12 and 13 are views illustrating the construction of the bobbin case. Fig. 14 is a view of the spindle upon which the thread is wound, also showing

the bobbin and bobbin case and another portion of the mechanism in central section. Fig. 15 is a side elevation showing the bobbin case open.

60

The same letters of reference indicate the same or corresponding parts in all the figures.

The thread *a* (Figs. 2, 4, 5, 6 and 9) for the supply of the bobbin is led from a reel or other holder *A* (supported upon a convenient bracket *a'*) through a groove *b* in the bed plate *B* and a hook-shaped guide *b*² (fixed to the bed plate) through another hook-shaped guide *b*³ onto a spindle *C*. 70 Upon this latter being rotated the thread is wound into a spool.

The spindle *C* is mounted in bearings *c*⁷ in line with the spindle *d'* of the bobbin case *D* and is loose in said bearings so that 75 it can be slid forward until its forward end is in contact with said spindle *d'* but is drawn back when the thread is to be wound onto it. When the machine is working the spindle *C* is rotated by a cog wheel *c'* keyed 80 loosely upon it and engaging with another cog wheel *c*² fixed upon a shaft *c*³. A clutch *c*⁴ keyed to this shaft *c*³ engages with a pulley *c*⁵ which is mounted loosely upon said shaft *c*³ and is rotated by an endless belt *c*⁶ 85 passing around the pulley upon the main or fly wheel shaft of the machine when the machine is being worked by hand. When the machine is being worked by treadle or motor, the belt used to drive the machine may 90 be caused to rotate said pulley *c*⁵ by contacting with it, as will be readily understood.

E represents a pusher piece mounted upon the spindle *C* and free to slide longitudinally thereon, its position being controlled by a fork *e'* projecting into an annular groove in said pusher piece. This fork *e'* is carried by a longitudinally sliding rod *e*², which can be moved by means of 95 a hand lever *e*³ pivoted upon a bracket *e*⁴ and projecting downward so that it can be readily moved by the operator, a slot in said hand lever *e*³ engaging with a pin *e*⁶ projecting from a block *e*⁷ fixed to the rod *e*². 100 The fork *e'* is also connected with the lever *e*³ by a spring *e*⁸ which serves to draw said fork *e'* and pusher piece *E* into their normal or winding positions.

A face plate *F*, corresponding in diameter with the pusher *E*, is pivoted at the end of a lever *f'* so that it can be rotated by the

110

spindle C when the end of said spindle projects into a hole in the center of said face plate. This end of the spindle C is slotted, as shown in Fig. 14, so that it engages with 5 a bar f^2 , which crosses the hole in the center of said face plate F and so causes said plate to revolve with the spindle C.

Four tapered cuts f^3 are arranged tangentially around the circumference of the 10 face plate F and serve to engage with the thread when a spool has been transferred to the bobbin and so causing said thread to be led around and wound onto the spindle C when this latter is rotated thereby forming 15 a short, broad spool between the face plate F and the pusher piece E, the diameter of said spool being controlled by a trip lever G described later.

The lever f' , upon which the face plate F 20 is pivoted, is fulcrumed upon a pin f^2 so that when it is desired to push a wound spool into the bobbin case the spindle may be drawn out of engagement with the face plate by a slight movement of the lever e^3 , 25 which action allows a spring f^5 to draw said face plate F into the position shown by dotted lines in Fig. 6.

A V-shaped guide f^7 is arranged to engage with one of a set of pins f^4 projecting 30 from the rear of the face plate in order to turn said face plate F into such a position that one of the slots f^8 will engage with the thread leading from the revolving hook D to the thread guide b^3 when the face plate is 35 drawn forward to enable a fresh spool to be wound. A curved blade or knife f fixed to the end of the lever f' is arranged to sever the thread when a fresh spool has been transferred to the bobbin, thereby cutting 40 said spool off from the supply reel A.

The trip lever G is pivoted upon a pin g^7 fixed to one of the brackets c^7 , which form the bearings of the spindle C and shaft c^3 ; its lower end being connected by a rod g^2 45 and pin g^3 to a block g^4 which can slide in a recess g^5 formed in a bracket g^6 while the upper end of said trip lever G bears against the spool of thread which is being wound upon the spindle C. Two pins g^3 , g^7 project from the block g^4 , the pin g^7 being fitted 50 with an anti-friction sleeve which bears against the lug h' projecting from a sliding rod H, this rod H being connected to a bifurcated lever h^2 pivoted upon a bracket h^3 55 and engaging with the clutch c^4 so that said lever h^2 controls the position of said clutch c^4 . This mechanism allows the spindle C to be rotated by the pulley c^5 ; clutch c^4 , etc., until a spool of the required size has been 60 wound when the levers G will force the pin g^7 against the pressure of a spring g^8 , until said pin is out of engagement with the lug h' , thereby freeing the rod H so that a spring h^4 can move said rod H and lever h^2 65 and thus throw the clutch c^4 out of engage-

ment with the pulley c^5 , thereby stopping the winding mechanism. The lug h' is shaped as shown in Fig. 1 so that the pin g^7 bears against a flat end for a certain distance and directly the pin gets past this end the 70 projection will act like a wedge, as it is drawn along by the spring h^4 and so force said pin g^7 outward, thereby drawing the trip lever G away from the spool and pusher piece E so that said trip lever will not catch upon them as the spool is being pushed toward the bobbin.

The member D is similar to an ordinary revolving hook, except that the sleeve or bobbin d^3 , which rotates upon the spindle d' contained within the bobbin case has only one flange, the second flange being replaced by a disk d^4 pivoted upon a cover d^5 so that said disk d^4 can revolve with said sleeve d^3 . This forms what may be called a one sided 80 bobbin. The cover d^5 is pivoted or hinged at d^6 in the base of the horn or projection d^7 which serves to keep the bobbin case from revolving by engaging with the bar or rod b^4 fixed to the bed plate B and formed so as to 90 fit over said horn or projection. This cover or door d^5 can be opened outwardly against the pressure of a small spring d^8 by a rod J when it is desired to replenish the supply 95 of thread on the bobbin. The rod J is mounted in bearings so that it can be slid forward until one end presses against a lug d^9 upon the cover or door d^5 of the bobbin case so that when said rod J is slid forward it opens said cover or door outwardly, as 100 shown in Fig. 4. The door of the bobbin case can only be opened when the revolving hook is in a certain part of its revolution (coincident with the needle being down) as at the other phases of the revolution the lug d^9 105 would foul with a part of said revolving hook. The rod J is bent into the shape shown so that it will not touch any part of the winding mechanism.

One of the bearings of the rod J is square 110 so that the rod cannot revolve. The longitudinal position of the rod J is controlled by an arm j' which projects from the rock shaft j^2 and engages with a pin j^3 fixed upon the rod J. The movement of this rock shaft 115 j^2 is controlled by an arm j^4 engaging with a block e^7 fixed to the rod e^2 . This mechanism causes the rod J to open the bobbin case door upon the first part of the movement of the pusher piece E when a wound 120 spool is being transferred to the bobbin. The bobbin case door is closed by the small spring d^8 at the end of the return movement of the pusher piece E, etc., (after a spool has been transferred to the bobbin). This 125 is caused by a pin e^9 (Fig. 9) projecting from the block e^7 engaging with an arm j^5 projecting from the rock shaft j^2 , and thereby withdrawing the rod J.

When it is desired to push a wound spool 130

into the bobbin case the operator moves the spindle C rearwardly *i. e.*, away from the bobbin case by pressing the hand lever e^3 in the direction of the arrow in Fig. 3, until 5 the end of the spindle C disengages with the face plate F, which latter will immediately be drawn to one side by the spring f^5 . The operator then moves the hand lever e^3 in the direction of the arrow in Fig. 4, forcing 10 the fork e' to slide the pusher piece E together with the wound spool and the spindle C forward until the spindle C is stopped by the end of the sleeve d^3 of the bobbin when the motion of the pusher piece 15 and spool being unchecked will slide the spool off the spindle C onto the sleeve d^3 . Upon the first part of this forward motion of the pusher piece, etc., the block e^7 will engage with the arm j^4 and cause the arm j' 20 of the rock shaft j^2 to push the rod J forward so that the end thereof will bear against the lug d^9 and thereby open the door d^5 , of the bobbin case. When the spool is being pushed into the bobbin case the end b^5 25 (Fig. 9) of a lever b^5, b^6 (pivotally mounted on the member e') engages with and is held back by the stationary bar b^4 which is fixed to the bed plate B. This action causes the lower end b^6 of this lever to swing forward 30 as its pivot is advanced and pull upon the thread leading from the hook b^3 to the spool and force it past a retaining spring which is constructed of a short length of steel wire d^{10} fixed to the bobbin case. This retaining 35 spring is adapted to close at the end of a slot d^{12} in the bobbin case (which is arranged to lead the thread under the tension piece d^{13}) by pressing upon the tongue d^{14} so that any thread drawn between said retaining 40 spring d^{10} and tongue d^{14} cannot be drawn out. A lug d^{15} , projecting from the cover or door d^5 of the bobbin case is arranged to cover the retaining spring d^{10} when the machine is working so that the top thread is 45 not caught by said retaining spring. The operator, having now pushed the wound spool on to the sleeve d^3 within the bobbin case, returns the hand lever e^3 to its normal position, *i. e.*, to that shown in Fig. 3, there- 50 by drawing the pusher piece E and spindle C away from the member D, this motion accomplishing the following operation. 1st. It causes the pusher piece E and spindle C to be drawn into their normal positions. 55 2nd. It causes the pin e^9 to engage with the arm j^5 of the rock shaft j^2 and thereby withdraws the rod J and allows the spring d^8 to close the bobbin case door d^5 . 3rd. It causes a pin e^{10} projecting from the hand 60 lever e^3 to contact with one end h^5 of a lever h^5, h^6 and thereby causes the opposite end h^6 of said lever to bear against the end of the rod H and thus forces said rod to move the clutch c^4 (by means of the lever h^2) un- 65 til said clutch engages with the pulley c^5 and the pin g^7 of the trip gear has engaged with the lug h' upon the rod H. 4th. When the rod H is moved by the lever h^5, h^6 , a lug h^7 projecting from said rod engages with an arm f^6 pivoted to the bracket e^4 and causes 70 the end of this arm to bear against the outer end of the lever f' , thereby drawing said lever f' into its normal position against the pull of the spring f^5 so that the face plate F is drawn forward into its normal or winding position. 75

The operation is now finished as far as the operator is concerned and the hand lever e^3 is let go. This action allows the small spring c^8 , which bears against the rear end of the spindle C, to press said spindle forward until its forward end projects into the center of the face plate. This last movement draws the fork e' forward so that a catch lever g^9 , which is pivoted to one of the 80 brackets c^7 , can be forced behind the said fork e' by a small spring g^{10} so that the said fork cannot be moved rearwardly. This catch lever g^9 is connected with the trip lever G by a slotted rod g^{11} pivoted to said lever 85 G, the slot serving to engage with the pin g^{12} upon one end of the catch lever g^9 so that said catch lever is drawn out of engagement with the rear side of the fork e' when the trip lever is forced outward upon the 90 completion of a spool. In action, this catch lever prevents the pusher piece E being forced away from the face plate F by the packing or wedging action of the thread as it is wound. 95

The operation of a sewing machine embodying my invention is as follows: Thread is led from a reel or other holder A through a groove b' in the bed plate B and through guides b^2, b^3 on to the spindle C and (this latter being rotated) is formed into a short broad spool between the pusher piece E and the face plate F. Said pusher piece revolves with the spindle C because a pin projecting from said spindle engages with said pusher 100 piece. When sufficient thread has been wound to constitute a spool of the required size the lever G will cause the pin g^7 to disengage with the lug h' upon the rod H, thereby allowing the spring h^4 to draw the clutch c^4 105 away from the pulley c^5 and thus stopping the winding mechanism when the machine will be used as an ordinary one until the supply of thread within the member D has been exhausted. When this happens the 110 operator turns the machine until the needle is down and then moves the lever e^3 so that the spindle C disengages with the face plate F and allows this latter to be drawn out of the way by its spring f^5 . The operator then 115 moves the hand lever in the reverse direction, thereby sliding the spool forward and also causing the rod J to open the door d^5 of the bobbin case. Upon the finish of this motion the spool is pushed well into the 120

til said clutch engages with the pulley c^5 125

member D and the thread which leads away from said spool, is engaged by the lever b^6 and is thereby forced past the retaining catch d^{10} upon the bobbin case. The lever e^3 is now moved into its normal position by the operator. This action returns all the parts to their normal positions and causes the clutch c^4 to connect with the drive pulley c^5 and also causes the face plate F to be drawn up into position. This face plate F will engage with the thread as it is drawn up into position, so that the thread will become jammed in one of the slots f^3 in said face plate and upon this latter being rotated the thread will be drawn around the curved blade f upon the end of the lever f' and so severed, thus cutting off the spool, now within the bobbin case, from the supply reel and holding the end of the thread to allow an entirely fresh spool to be wound, upon the completion of which the winding gear will be stopped as before. It will be seen, therefore, that the end of the thread leading from the supply is held by the gripper f^3 to enable the spool to be wound upon the revolving spindle C. When the head F is swung out of the way on the completion of the spool, the end of the thread pulls out of the gripper. Then as the pusher shoves the completed spool into the bobbin, the thread between the spool and the supply comes across a gripper and the knife, and the thread is severed between the gripper and the bobbin, the thread from the supply being held as before by the gripper for the next spool. The length of thread which now projects from the revolving hook is in position to be caught by the top thread in the needle and drawn up under the tension piece d^{13} upon the bobbin case, the machine being operated as an ordinary one until the supply of thread upon the bobbin again requires replenishing.

The different operations performed by the mechanism and operator may be summarized as follows:—A spool is wound on to the spindle and the winding stopped when said spool is of the required size. This spool is pushed into the bobbin case and the revolving hook D threaded. The mechanism is withdrawn into its normal or winding position and the spool cut from the supply reel and the clutch mechanism is connected so that a fresh spool may be wound.

Having thus described my invention, what I claim is:—

1. In a sewing machine, the combination of a case for a rotary bobbin, a rotary bobbin located in the case, a rotary spindle, means for winding thread upon the spindle, and means for transferring it to the bobbin in the case.

2. In a sewing machine, the combination of a case for a rotary bobbin, a rotary bobbin located in the case, a spindle alined there-

with, means for winding thread upon the spindle, means for shoving such thread lengthwise of the spindle onto the bobbin in the case.

3. In a sewing machine, the combination of a rotary bobbin having a central spindle, a spindle alined therewith, means for winding thread in a coil on the last named spindle, means for bringing the two spindles substantially into engagement, and means for shoving the thread from the spindle on which it is wound onto the spindle of the bobbin. 70

4. In a sewing machine, the combination of a rotary bobbin, a spool winding spindle mounted in bearings in line with the bobbin, a removable face plate for such spindle, and means for transferring the spool from the spindle to the bobbin. 75

5. In a sewing machine, the combination, with a revolving hook, a bobbin mounted in said hook, a spool winding spindle, a lever, a movable face plate revolubly mounted on the lever and adapted to form a wall for a spool being wound on the spindle, another face plate forming the other wall for such spool, and means for transferring the spool from the spindle to the bobbin. 80

6. In a sewing machine, in combination, a rotary bobbin, a spool winding spindle mounted in bearings in line with the axis of the rotary bobbin, a removable and revolute face plate adapted to stand at the end of the spindle, means for removing such face plate, and means for transferring the wound spool from the spindle to the bobbin. 85

7. In a sewing machine, the combination, with a revolving hook rotary spindle, of a removable and revolute face plate coöperating therewith and having one face against which the spool wound on the spindle is formed, said face plate being formed with tapered tangential cuts, means for guiding the thread to the spindle, means for rotating the spindle, a rotary bobbin, and means for transferring the spool from the spindle to the bobbin. 90

8. In a sewing machine, the combination, with a revolute spindle, of a removable and revolute face plate fitting against one end of the spindle and having projecting pins on its rear face, a guide with which said pins may coöperate to properly hold the face plate when stationary. 110

9. In a sewing machine, the combination, with a rotary winding spindle, of a removable and revolute face plate adapted to form one wall against which the spool being wound on the spindle is formed, a cutting plate carried by the support for the face plate. 115

10. In a sewing machine, the combination of a rotary spindle, a head slidable thereon, a removable face plate, said head and face plate and spindle forming a guide on which 120

- the thread may be wound, means for removing said face plate, means for causing the head to move along the spindle to shove the wound spool off of the spindle, and a bobbin case adapted to carry a rotary bobbin having a central spindle in alinement with the winding spindle, whereby the wound thread may be shoved from the winding spindle onto the bobbin spindle.
11. In a sewing machine, the combination, with a revolving hook, a bobbin case adapted to carry a bobbin having a central spindle, of a rotary winding spindle in line with the bobbin spindle, mechanism for winding thread onto the winding spindle mechanism for then bringing the winding spindle into substantial engagement with the bobbin spindle, and mechanism for then shoving the wound thread lengthwise of the winding spindle onto the bobbin spindle.
12. In a sewing machine, the combination, with a rotary bobbin having a central spindle, a rotary winding spindle, means for holding such spindles in axial alinement, a pair of heads coöperating with the winding spindle and providing a space between which the spool may be wound, means for removing the head between the spindle and bobbin, and means for moving the other head lengthwise of the spindle to shove the spool onto the bobbin.
13. In a sewing machine, the combination, with a rotary bobbin, means for carrying it, a rotary spindle, a pair of heads coöperating therewith and providing a space in which the thread may be wound around the spindle, means for removing the head which is between the spindle and bobbin, means for shoving the other head lengthwise of the spindle toward the bobbin, and a spring adapted to hold the spindle in proximity to the bobbin as the thread is being transferred.
14. In a sewing machine, the combination, with means for winding a spool of thread, a rotary bobbin, means for shifting said spool onto the bobbin, means for controlling the shifting, and a trip lever actuated by the thread on the spool and controlling the last mentioned means.
15. In a sewing machine, the combination of a revoluble winding spindle, a lever, a face plate rotatably mounted on the lever, a spring for withdrawing such lever, means for moving it to bring the face plate into position opposite the end of the spindle, a bobbin, and means for removing the wound spool from the spindle when the face plate is away from the spindle and depositing it onto the bobbin.
16. In a sewing machine, the combination of a revolving hook, a rotary bobbin, mechanism for winding a coil of thread, mechanism for depositing it on the bobbin, and mechanism for threading the revolving hook.
17. In a sewing machine, the combination of a bobbin case having a door, a bobbin mounted within the bobbin case, mechanism for winding thread for the bobbin, mechanism for inserting the same into the bobbin case, and mechanism for automatically opening the door of the bobbin case just preceding the insertion of the thread thereinto.
18. The combination in a sewing machine, of a revolving hook, a bobbin case about which the revolving hook is adapted to rotate, a bobbin within said bobbin case, mechanism for winding thread to form a spool, and mechanism for transferring such spool onto the bobbin.
19. In a sewing machine, the combination of a rotary bobbin, a spindle whose axis alines with the bobbin, mechanism for winding thread into a spool on said spindle, and mechanism for shoving such spool lengthwise of the spindle onto the bobbin.
20. In a sewing machine, the combination of a bobbin case having a cover or door hinged to it, a one-sided bobbin within such case, mechanism for winding a spool of thread, and mechanism for opening such door and inserting said spool.
21. In a sewing machine, the combination of a bobbin having a central spindle and one disk-like flange extending therefrom, mechanism for winding a coil of thread, and mechanism for shoving such coil bodily onto the spindle of the bobbin.
22. In a sewing machine, the combination of a bobbin case having an axial spindle, a door hinged to said case, a spring tending to close said door, mechanism for winding thread into a spool, and mechanism for opening said door and inserting said spool around the spindle of the bobbin case.
23. In a sewing machine, the combination of a rotary bobbin case having an axial spindle, a bobbin within said case having a sleeve seating on said spindle and a disk-like flange at the rear end of said sleeve, a door pivoted to the bobbin case, mechanism for winding thread into a spool, mechanism for opening said door, mechanism for bringing the wound spool into juxtaposition to the bobbin sleeve, and means for shoving said spool lengthwise onto said sleeve.
24. In a sewing machine, the combination of a bobbin case having a central spindle, a bobbin having a sleeve on said spindle and a disk-like flange at its rear end, a winding spindle alined with said sleeve, means for winding thread into a spool around said spindle, a head slidable on said spindle, and means for moving said head to shove the wound spool onto the sleeve of the bobbin.
25. In a sewing machine, the combination of a bobbin means for winding thread

- into a spool to be transferred thereto, a trip lever adapted to bear against layers of thread on the spool, a clutch for controlling the winding mechanism, an operating connection between the trip lever and the clutch whereby the trip lever may throw the clutch, and mechanism whereby the trip lever is thrown out of the path of the spool when it operates the clutch.
26. In a sewing machine, the combination of mechanism for winding a thread into a spool, a rotary bobbin, mechanism for transferring the spool onto the bobbin, and mechanism for severing the thread between the spool and the supply thereof.
27. In a sewing machine, the combination

of mechanism for winding a thread into a spool, a bobbin, mechanism for transferring the spool onto the bobbin, mechanism for severing the thread between the spool and the supply thereof, and means for automatically grasping and holding the end of the thread after severance adjacent to the winding mechanism for subsequent winding.

In testimony whereof I have hereunto set 25 my hand in presence of two subscribing witnesses this tenth day of May 1904.

FREDERICK BAKER.
